WORK SHIFTER

John Robertson Lamberton, Coatbridge, Scotland

Application February 25, 1935, Serial No. 8,148
In Great Britain September 14, 1933

5 Claims. (Cl. 80—48)

This invention relates to improvements in 5 tilter devices for use in tilting metal billets and sections to be rolled, being particularly applicable to devices for use in tilting and holding up square or approximately square or diamond-shaped billets when rolling in diamond passes.

A tilter device comprising a cooperative pair of work-engaging heads constructed in accordance with the present invention is illustrated in 10 the accompanying drawings in which Fig. 1 is an end elevation, Fig. 2 a plan view, Fig. 3 a longitudinal vertical section on the line *a—a* of Fig. 1, and Figs. 4-6 fragmentary views of the tilter heads.

15 The tilter device shown comprises a pair of tilter heads *1*, *1^a* constituted as fluted conoidal members adapted for engagement in opposed relation with a metal billet *2* undergoing treatment in a rolling mill.

20 Each tilter head *1* or *1^a* is fixed to or unitary with a toothed sector *3* mounted for partial rotation about its axis *4* in a link structure including a pair of links *5* mounted for pivotal movement about the axis *6* of a pinion *7* meshing with the sector *3* and with a pinion *8* on a shaft *9* carrying also a gear wheel *10* meshing with a pinion *11* on the rotor shaft of a reversible electric driving motor *12*. The axis *4* of the sector *3*, the axis *6* of the pinion *7*, the axis of the shaft *9* and the axis of the pinion *11* are all parallel to the 30 line of travel of the billet through the mill.

The arrangement is such that each sector *3*, as well as being rotatable about its own axis *4* by actuation of the respective electric motor *12*, is free to move bodily in an arc about the axis *6* spaced from the axis *4* in accommodating itself to the movement of the billet *2*.

40 Each tilter head *1* or *1^a* may be moved to an inoperative upper position as at *A* or an inoperative lower position as at *B* (Fig. 1).

Each tilter head assembly is incorporated in a frame structure *13* or *13^a* mounted upon the feed table of the rolling mill and movable transversely of the line of travel of the billet *2*. *14* 45 denotes the roll housing of the rolling mill.

In operation, the tilter heads *1* and *1^a* are suitably angularly adjusted to tilt the billet in the required direction, one head being used as an abutment and the other head being actuated to tilt the billet, as shown in Figs. 4 and 5, in which figures the head *1* is serving as the abutment and the head *1^a* as the manipulating head, it being understood that the head *1^a* is traversed towards the abutment-forming head *1* in the manipulation of the billet. Figs. 4 and 5 show the heads

5 operating on a billet of comparatively large size, while Fig. 6 shows the heads operating on a billet of comparatively small size. As is understood, the sector *3* of the manipulating head *1^a* is floatingly supported by the respective pair of links *5* which thus permit the sector to adjust itself vertically as required in the co-operation of the head *1^a* with the billet *2*.

I claim:—

1. In a metal rolling mill, a tilter device comprising at least one movable tilter head, a toothed sector carrying said tilter head having its axis parallel with the direction of travel of the work, and a pinion meshing with said sector and having its axis parallel with and spaced from the axis of said sector, said sector being rotatable about its own axis, and movable bodily in an arc about the axis of said pinion. 10

2. In a metal rolling mill, a tilter device movable transversely of the direction of travel of the work, said device comprising a work-engaging head, a toothed sector carrying said head and rotatable about an axis parallel with the direction of travel of the work, a pinion meshing with said sector and having its axis parallel with and spaced from the axis of said sector, and a link structure mounted for pivotal movement about the axis of said pinion and carrying said sector. 20

25 3. In a metal rolling mill, a frame movable transversely of the direction of travel of the work, and a tilter device incorporated in said frame, said tilter device comprising a work-engaging head, a toothed sector carrying said head, and having its axis parallel with the direction of travel of the work, a pinion meshing with said sector and journalled in said frame for rotation about an axis parallel with and spaced from the axis of said sector, and a structure mounted for pivotal movement about the axis of said pinion and carrying said sector. 30

35 4. In a metal rolling mill, a frame movable transversely of the direction of travel of the work, and a tilter device incorporated in said frame, said tilter device comprising a work-engaging head, a toothed sector carrying said head, and having its axis parallel with the direction of travel of the work, a pinion meshing with said sector and journalled in said frame for rotation about an axis parallel with and spaced from the axis of said sector, a structure mounted for 40

45 pivotal movement about the axis of said pinion and carrying said sector, a reversible motor mounted on said frame for rotation about an axis parallel to the axis of said sector, and a gear train connecting said motor with said pinion. 50

5. In a metal rolling mill, a tilter device movable transversely of the direction of travel of the work, said tilter device comprising a work-engaging head, a toothed sector carrying said head, and having its axis parallel with the direction of travel of the work, a pinion meshing with said sector and having its axis parallel with and

spaced from the axis of said sector, links mounted for pivotal movement about the axis of said pinion and carrying said sector, a reversible motor rotatable about an axis parallel with the axis of said sector, and a gear train connecting said motor with said pinion.

JOHN ROBERTSON LAMBERTON.
